UNITED STATES PATENT OFFICE.

FREDA LOVE PERKINS, OF DENVER, COLORADO.

DESIGN FOR A SHADE FOR ILLUMINATING DEVICES.

SPECIFICATION forming part of Design No. 37,012, dated June 28, 1904.

Application filed May 25, 1904. Serial No. 209,801. Term of patent 3½ years.

To all whom it may concern:

Be it known that I, FREDA LOVE PERKINS, a citizen of the United States of America, residing in the city and county of Denver and State of Colorado, have invented a new, original, and ornamental Design for a Shade for an Illuminating Device, reference being had to the accompanying drawings, which form a part of this specification.

This invention relates to a new, original, and ornamental design for a shade for an illuminating device, the said design being illus-

trated in the accompanying drawings, in which—

Figure 1 is a side elevation of a shade, showing my design. Fig. 2 is a top plan view of the same.

What I claim is—

The ornamental design for a shade for an illuminating device as shown in the drawings.

FREDA LOVE PERKINS.
